UNITED STATES PATENT OFFICE

2,577,189

SHUFFLEBOARD CUE

Clarence E. Hammett, South Gate, Calif., assignor
to Young Francis Hammatt, Anaheim, Calif.

Application January 21, 1949, Serial No. 71,958

2 Claims. (Cl. 273—129)

1

My invention relates to a cue or pusher which is used when playing the game of shuffleboard, and which is different from prior devices in regard to the method and means employed for pushing the shuffleboard disc and attaching the head member to the handle.

The primary object of my improvement is to provide means by which the shuffleboard disc is more effectively engaged when playing and whereby the head member of the device can be easily disjointed from the handle or reassembled for use.

Heretofore shuffleboard cues have been so constructed that continuous use has caused excessive wear due to the shuffleboard cue and disc being constructed out of wood. In other words the rubbing surface of contact on runways or lanes, plus weight, retards the free use of the device. The abuse that shuffleboard cues are subjected to on public courses, makes it necessary to frequently replace the head member or entire cue. This is expensive and makes it necessary to maintain a supply of parts or complete cues on hand. My invention enables the head member to be easily and quickly detached and either repaired or replaced at minimum expense. The head member is preferably made out of metal or other suitable wear resisting material and is light in weight and its points of engaging contact with the shuffleboard disc are evenly balanced so as to enable the player to more accurately play the game of shuffleboard.

My improved shuffleboard cue has maximum strength of construction and life, and if deliberately abused by an irate player, it will not usually be broken. However, if broken or bent out of balance, a new head member can easily be installed without the use of tools by anyone, or the old head member can be easily removed, repaired and replaced. The simplicity of my improved shuffleboard cue together with its light weight, even balance of contact against the perimeter of the shuffleboard disc, and small contact on the surface of the shuffleboard course, commends itself for use by players of the game of shuffleboard. These features also facilitate manufacture of the device.

In the accompanying drawing forming part of this specification, Fig. 1 is a plan of my improved shuffleboard cue, part of the handle being in section and a shuffleboard playing disc being shown in position to be engaged by my improved shuffleboard cue or pusher head member; Fig. 2 is a perspective view of the shuffleboard cue or pusher head when removed from the handle; Fig. 3 is a

2

side elevation of the shuffleboard cue or pusher head member; and Fig. 4 is a section, at enlarged scale, on the line 4—4 of Fig. 1.

In the drawing, A indicates my improved shuffleboard cue or pusher head member, B a pusher handle, and C a shuffleboard playing disc with which said head is shown in contact in Fig. 1 for illustrating my improved device when in use. The pusher head member A is constructed out of a single piece or rod of metal or other suitable material, bent nearly midway between its ends into a furcation 10, the forward side ends of which are shaped into a pair of curved shuffleboard disc engaging contact loops 12 and 13 and a pair of rearwardly extending flexible side arms 14 and 15. The rearward ends of these side arms at a spaced interval back of the furcation 10 and the contact loops 12 and 13 are curved inwardly and terminate rearwardly in a pair of parallel supporting arms 16 and 17, which are spaced apart and adapted to removably engage the handle B in a corresponding pair of longitudinal grooves or channels 18 and 19 therein. The contact loops 12 and 13 are sufficiently spaced apart to insure accuracy and even balance at a proper distance apart while engaging the shuffleboard disc and when playing the game of shuffleboard. The contact loops 12 and 13 are also struck upwardly and forwardly as shown in Figs. 2 and 3, so as to elevate the points of contact against the perimeter of the disc-like play element C, above the surface of the runway, lane or other play surface on which the shuffleboard game is played.

The downwardly slanting furcation is adapted to slide or glide over the play surface as the shuffleboard cue is applied to a play member such as C.

The shuffleboard cue or pusher head member A is easily detached from or attached to the forward end of the handle B, when desired, by the longitudinal arm members 16 and 17, which engage in the corresponding pair of longitudinal key grooves or indentures 18 and 19. The rearward ends of the arm members 16 and 17 are struck inwardly and formed with key shoulders 20 and 21 which engage in key indentures 22 and 23 in the handle bar. A sleeve 24 is adapted to slide longitudinally on the handle bar B and engage and hold the arms tightly secured in the key channels 18 and 19 while said shoulders are in locked engagement. In this manner the head is supported rigidly and can be easily and quickly removed and replaced on the handle in case of any accident and when a head is bent or injured.

In use the furcation 10 forms a free sliding

contact on the play surface and enables the player to poise the head member with its contact points suitably adjusted and evenly balanced against the perimeter of the shuffleboard disc and at most effective elevation, thus insuring accuracy of play. During this use the head member is removably maintained and prevented from turning by the handle. The key shoulders 20 and 21 are staggered in position longitudinally so as not to weaken the handle B by the relative position of 10 the indentures 22 and 23.

Modifications are contemplated within the spirit of the invention and within the scope of the following claims.

I claim:

1. An implement for sliding a disc-like play member on a play surface, comprising a rod structure having forwardly and upwardly directed points of contact spaced apart laterally and applicable against the perimeter of said disc-like member, a slide member connected to and converging downwardly and rearwardly between said points of contact, and a pair of supporting side arms above said slide and extended rearwardly from said points of contact in a plane above said 25 slide.

2. An implement for propelling a disc-like play member on a play surface, comprising a wire structure formed with a plurality of upwardly extended points of contact spaced laterally apart for contact with the perimeter of said play member and a V-shaped furcation supporting slide member connected to and extended downwardly and pointed rearwardly between said contact members.

CLARENCE E. HAMMETT.
